CLAIM

The ornamental design for a medical apparatus for imaging, as shown and described.

DESCRIPTION

FIG. 1 is a front elevational view of a medical apparatus for imaging showing our new design;
FIG. 2 is a back elevational view thereof;
FIG. 3 is a top plan view thereof;
FIG. 4 is a bottom plan view thereof;
FIG. 5 is a right side elevational view thereof;
FIG. 6 is a left side elevational view thereof; and,
FIG. 7 is a perspective view taken generally from the front, top, and right-hand side thereof.

The broken lines shown in the drawings represent portions of the medical apparatus for imaging that form no part of the claimed design.
